UNITED STATES PATENT OFFICE.

FERDINAND UNCKRICH, OF GALION, OHIO.

VAULT-CLOSURE.

959,406.

Specification of Letters Patent. Patented May 24, 1910.

Application filed May 15, 1908. Serial No. 433,010.

To all whom it may concern.

Be it known that I, FERDINAND UNCKRICH, a citizen of the United States, and a resident of Galion, in the county of Crawford and State of Ohio, have invented a new and Improved Vault-Closure, of which the following is a full, clear, and exact description.

This invention relates to vault closures and constitutes an improvement upon the vault closure covered in my Patent No. 872,864, dated December 3, 1907.

More particularly, the invention relates to a vault closure intended for locking and hermetically sealing grave vaults and the like, and consists of a door which can be locked in position at a door frame so that it cannot be opened from the outside without destroying the door frame or the door, and which further, can be so adjusted that if desired it can be opened from the outside without injury thereto, after it has been locked in position.

An object of the invention is to provide a closure by means of which the vault opening can be covered by the vault door, which is securely locked from the outside, and which effects a hermetical sealing of the vault opening.

A further object of the invention is to provide a closure for vault or other openings, which can be so arranged that it is impossible to open the door from the outside after it has once been locked in position, and which can be further arranged so that it is possible to open the door from the outside without injury to the door or the door frame.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is an elevation of the inner face of the vault closure showing the locking mechanism in an inoperative position prior to projecting the locking bolts of the door behind the door frame to secure the door in place; Fig. 2 is a similar view of a part of the invention showing the locking mechanism in an operative position; Fig. 3 is an

enlarged vertical section of the door frame and the foot of the closure; Fig. 4 is a similar view showing certain of the parts in different positions; Fig. 5 is a longitudinal section on the line 5—5 of Fig. 3; and Fig. 6 is a similar view on the line 6—6 of Fig. 4.

Before proceeding to a more detailed explanation of my invention, it should be understood that while it is particularly useful in connection with the closures or doors of grave vaults or the like, it can also be advantageously employed for locking doors or closures of different types in position at openings of other structures. It is desirable in many cases, to provide grave vaults and the like with strong, durable and hermetically sealed closures for the openings therefor, to prevent unauthorized admission to the vaults, and to insure the preservation of the contents of the same. I provide a vault closure comprising a door plate adapted to seat against a door frame. The plate and frame are preferably of steel, iron or the like.

The door frame may be secured at the vault opening by means of bolts or rivets or in any other suitable manner, depending upon the construction of the vault, which may be of metal, stone-work or the like. Slidably mounted upon the inner side of the door plate are bolt members which can be projected toward the edges of the door behind the lateral flanges of the door frame, thereby locking the door in position against the frame. The bolt members are projected by means of a rotatable cam having lobes engaging with the bolt members to thrust them outwardly toward the edge of the door plate when the cam is rotated. A key-bolt member is arranged near the center of the door plate and has a threaded part located in a suitably threaded opening in the cam member. The key-bolt presents a squared head at the outer face, by means of which the operating mechanism can be actuated with the end of a suitable wrench or other tool. A frangible member comprising preferably, a soft metal plug, serves to secure the cam member to the key-member so that when the latter is projected, the cam is similarly actuated to project the bolts.

When the bolts are projected to the limit of their movement, the rotation of the cam

member is resisted, whereupon the frangible member is broken. When this takes place the key-bolt member is free to turn in the threaded opening in the cam member, 5 whereupon the cam is forced outwardly from the face of the door plate and carries with it by means of a projecting annular shoulder, the bolt members. By thus forcing the bolt members outwardly, the door plate is clamped against the door frame to effect the hermetical sealing of the vault opening.

The key bolt member has a ratchet which is received in a suitably formed recess of 15 the cam, and when the latter is forced outwardly by the continued rotation of the key-bolt member, after the frangible plug has been broken, a dog drops into engagement with the ratchet and thus prevents the backward rotation of the key-bolt member.

The cam has a recess formed to receive a tongue carried by one of the bolts and this, too, serves to lock the cam in position, and prevents a forward or backward rotation of 25 the cam. In the present improved form of my invention the bolts are operatively connected with the cam by means of pivoted links which assist in projecting the bolts when the cam is operated. The cam has a 30 recess formed to receive the tongue in a certain position of the former so that the cam can turn in one direction only, though free to turn in the other direction. This construction permits the cam to be turned so 35 that its lobes pass beyond the bolts and the latter can return to their inoperative positions when the key-bolt member is further rotated, and when the frangible member remains unbroken. This permits the vault to 40 be opened from the outside, if it is not desired to permanently close the vault; for example, if at later times admission to the vault is necessary.

Referring more particularly to the drawings, 1 represents a vault having an opening 2 with the door-frame 3 arranged therein. The door-frame 3 has an inwardly disposed flange 4 and is secured in place by means of screws or rivets, or in any other 45 convenient manner. Seating against the door-frame is a door-plate 6 having at the outer face a central boss 9 and strengthening ribs 10. A key-member 11 is carried by the door plate in a suitable opening and has a 50 squared head 12 projecting beyond the outer door face, so that it can be easily manipulated by means of a suitable tool. The key-member 11 has a threaded part 13 extending beyond the inner face of the door plate and 55 it is further provided with an annular shoulder 14 normally seating against the inner face of the door. The annular shoulder 14 is provided with peripheral teeth 7 constituting a ratchet. A cam member 15 is 60 mounted upon the threaded part 13 of the

key-member by means of a suitably threaded opening therethrough. The cam member 15 has cam lobes 16 and a laterally extended annular flange 17 normally adjacent to the inner face of the door.

Bolts 22 are slidably mounted upon the inner face of the door and are cut away for the purpose of reducing the weight, and the amount of material necessary therefor. They are preferably triangular in form and 75 have the apexes adjacent at the center of the door plate. At the sides adjacent to the corresponding sides of the door plate the bolts have toes 23 having recesses 24 arranged to receive studs 25 rigid with the door plate. 80 The studs have cross bars 26 which engage at the inner sides of the toes 23 and guidance hold the bolts upon the door frame. Each of the bolts has a central slot 27 which receives a lug 28 rigid with the door plate, 85 and serving to guide the bolts. A helical spring 29 is arranged in each of the slots 27 between the lug 28 and an end of the slot, whereby the bolt is normally forced inwardly beyond the plate edges in an inoperative position. At the apex, each bolt has a cut away portion having a shoulder 30 adapted to engage a shoulder 31 of the cam to prevent the rotation of the cam member in one direction.

A dog 19 is pivotally mounted upon the face plate and is normally held out of engagement with the ratchet 7, owing to the interposition of the annular flange 17, the cam member having a recess 20 which receives the ratchet 7 when the cam is in its normal position against the door plate. Links 32, pivotally mounted by means of screws 33 or the like, operatively connect the cam and the bolts to assist in projecting the latter when the cam is rotated. It will be understood that the engagement of the cam lobes with the apexes of the triangular bolts, force the latter outward beyond the edges of the door plate as the key-member is rotated, the cam turning with the key-member owing to the provision of a frangible plug or a block 34, between the ratchet and the recess 20, the latter having an extension 35 at one side, which receives the plug 34. The 115 plug 34 is positioned in the extension 35 and between two adjacent teeth of the ratchet, as is shown most clearly in Fig. 5.

One of the bolts has a recess 36 in which is slidably arranged a tongue 37 normally projected by means of a helical spring 38 arranged within the recess. One of the lobes of the cam has a notch 39 which is adapted to receive the end of the tongue when the cam is moved into a predetermined position. 120 When the tongue engages the notch as is shown in Fig. 2, the cam is held against rotation in either direction and the bolts are then secured in the projected positions. The adjacent lobe of the cam has an edge 130

recess 40, which, as will appear more clearly hereinafter, is adapted to receive the tongue and to hold the cam against rotation in one direction. At the under side, each of the 5 bolts has recesses 41 in which are positioned helical springs 42 engaging the door plate and normally tending to force the bolts outward from the door plate. The outward movement of the bolts is resisted and limited 10 by the cross bars 26 of the studs 25.

In the normal condition of the closure, the bolts are withdrawn from the edges of the door plate and the cam rests against the inner face of the same, as is shown most 15 clearly in Fig. 1, the key-bolt member and the cam being operatively connected by means of the frangible plug 34. When it is desired to close the opening of the vault, the door is placed in position, with the edges 20 engaging the flange of the door frame and if so desired, with the interposition of a gasket 43 between the door frame and the door. The key bolt member 12 is then turned and the cam is thereby actuated to project the 25 bolts to the inside of the flange of the door frame, thus locking the door in position. As soon as the tongue 37 slips into engagement with the notch 39, further movement 30 of the cam is prevented and if the key-bolt member is further rotated the frangible member is ruptured. A continued rotation of the key-bolt member then forces the cam outwardly owing to the provision of the threaded part 13.

35 The movement of the cam away from the door plate carries the bolts with it, as the flange 17 is positioned underneath the apexes of the bolts. The latter act as levers, the cross bars 26 serving as fulcrums, and 40 thus clamp the door plate securely against the door frame, as is shown most clearly in Fig. 4. The movement of the cam away from the door plate leaves the dog 19 free to come into engagement with the ratchet 7 45 whereby, too, a return movement of rotation of the key-bolt member is prevented. In this way the closure is permanently locked in position and effects a hermetical sealing of the opening of the vault, and it 50 is impossible to obtain admission to the vault without destroying the closure.

If it is desired to close the vault, but not to do so permanently, the links 32 can be removed at their cam ends and the cam 55 turned so that the edge recess 40 will be engaged by the tongue when the bolts are projected. The links can then be again secured to the cam and the door placed in position. When the key-bolt member is 60 now turned the bolts will be projected and the tongue will slip into engagement with the edge recess 30. As the latter engages the tongue at one side only, thereof it is possible to continue the movement of the cam 65 until the lobes pass beyond the apexes of

the bolts, whereupon the latter under the influence of the springs 29 will return to an inoperative position to permit the door to be opened.

Having thus described my invention, I 70 claim as new, and desire to secure by Letters Patent:

1. A vault closure comprising a door adapted to seat against a door frame, bolts carried by said door, a key member having 75 an initial movement adapted to project said bolts behind said frame, and having a second movement adapted to clamp said bolts against said frame, and links for operatively connecting said key member and each of 80 said bolts.

2. A vault closure, comprising a door adapted to seat against a door frame, slideable bolts, means for successively projecting said bolts toward said frame and forcing 85 said bolts into inclined positions with respect to the face of said door to clamp said bolts against said frame, and links operatively connecting said means and said bolts.

3. A vault closure, comprising a door 90 adapted to seat against a door frame, bolts movably mounted on said door, an operating member formed in sections and serving to project said bolts, a frangible member connecting said sections and adapted to be 95 broken when said bolts are forced home, means for clamping said bolts against said frame by the continuous movement of said operating member, a member preferably a dog for locking said operating member 100 against a return movement, and links operatively connecting said operating member and said bolts.

4. A vault closure, comprising a door adapted to seat against a door frame, bolts 105 movably mounted upon said door, an operating member controlling said bolts to project the same, and a resiliently projected tongue whereby one of said bolts, when projected, controls said operating member to 110 lock the same against a return movement.

5. A vault closure, comprising a door adapted to seat against a door frame, bolts movably mounted upon said door, and an operating member controlling said bolts to 115 project the same, one of said bolts having a normally projected tongue whereby when said bolt is projected, said tongue engages said operating member to lock the same against a return movement, said operating 120 member being adapted by a continuous movement to clamp said bolts against the door frame when said bolts are projected.

6. A vault closure, comprising a door adapted to seat against a door frame, bolts 125 movably mounted upon said door, one of said bolts having a normally projected movable tongue, and an operating member controlling said bolts to project the same, said operating member having a recess adapted 130

to receive said tongue when said bolts are projected, whereby said member is locked against movement.

7. A vault closure, comprising a door adapted to seat against a door frame, bolts movably mounted upon said door, one of said bolts having a normally projected movable tongue, and an operating member controlling said bolts to project the same, said member having a recess adapted to receive said tongue when said bolts are projected, whereby said member is locked against movement in one direction.

8. A vault closure, comprising a door adapted to seat against a door frame, slideable bolts carried by said door, a key-member mounted upon said door, a cam carried by said key-member and adapted to project said bolts when said key-member is operated, said key-member having means controlled by its movement for clamping said bolts when the latter are projected, against said door frame, one of said bolts having a normally projected movable tongue, said cam having a recess adapted to receive said tongue when said cam is in a position such that said bolts are projected, whereby said cam is locked against movement.

9. A vault closure, comprising a door adapted to seat against a door frame, bolts movably mounted on said door, an operating member formed in sections to project said bolts, a frangible member connecting said sections and adapted to be broken when said bolts are forced home, means for clamping said bolts against said frame by a continuous movement of said operating member, springs tending normally to force said bolts outward from said door, and means for guidingly holding said bolts in position against said door.

10. A vault closure, comprising a door adapted to seat against a door frame, bolts carried by said door and having slots, lugs rigid with said door and received by said slots, springs in said slots and engaging said lugs, whereby said bolts are held in normal positions, a key-member having an initial movement adapted to project said bolt's behind said frame and having a second movement adapted to clamp said bolts against said frame, springs tending normally to force said bolts outward from said door, means for guidingly holding said bolts against said door, and links operatively connecting said key member and said bolts.

11. A vault closure, comprising a door adapted to seat against a door frame, bolts carried by said door, a key-member having an initial movement adapted to project said bolts behind said frame and having a second movement adapted to clamp said bolts against said frame, and a dog for preventing the rotation of said key-member in one

direction, said dog being normally inoperative and being rendered operative by the second movement of said key-member.

12. A vault closure, comprising a door adapted to seat against a door frame, bolts movably mounted on said door, an operating member formed in sections to project said bolts, a frangible member connecting said sections and adapted to be broken when said bolts are forced home, means for clamping said bolts against said frame by a continued movement of said operating member, and a dog for preventing the rotation of said key member in one direction, said dog being normally inoperative, and being rendered operative by the second movement of said operating member, and links connecting one of said sections of said operating member with said bolts.

13. A vault closure, comprising a door adapted to seat against a door frame, slideable bolts carried by said door, a key-member mounted upon said door, a cam carried by said key-member and adapted to project said bolts when said key member is operated, said key-member having means controlled by its movement for clamping said bolts when the latter are projected against said door frame, one of said bolts having a normally projected movable tongue, said cam being formed to receive said tongue when it is in a position such that said bolts are projected, whereby said cam is locked against further movement, and a dog for preventing the rotation of said key-member in one direction, said dog being normally inoperative and being rendered operative by the movement of said key-member to clamp said bolts.

14. A vault closure, comprising a door adapted to seat against a door frame, slideable bolts carried by said door, a rotatable key member, a cam having lobes adapted to project said bolts, a frangible member connecting said key-member and said cam, said cam having shoulders engaging said bolts, said key member having a ratchet, said cam having a recess adapted to receive said ratchet when said cam is in a normal position against said door, a dog adapted to engage said ratchet and held from engagement therewith by said cam when the same is in a normal position, means carried by said key member for forcing said cam away from said door when said frangible member is broken, and means on one of said bolts for engaging said cam to lock the same against rotation when said cam is in a position such that said bolts are projected.

15. A vault closure, comprising a door adapted to seat against a door frame, slideable bolts carried by said door, a rotatable key member carried by said door and having a threaded section, said key member being operable from the outer side of said door, a

cam having lobes adapted to project said bolts and arranged upon said threaded section of said key member at the inner side of said door, said key member having a 5 ratchet, said cam having a recess adapted to receive said ratchet when said cam is in a normal position against said door, a frangible member connecting said ratchet and said cam; said cam having a shoulder positioned between said door and said bolts and 10 engaging the latter, a dog adapted to engage said ratchet and held from engagement therewith by said cam when the same is in a normal position, one of said bolts having 15 a normally projected movable tongue, said

cam having a recess adapted to receive said tongue whereby said cam is held against movement, said cam further having a recess adapted to receive said dog, whereby said cam is held against movement in one 20 direction, and links operatively connecting said cam and said bolts.

In testimony whereof I have signed my name to this specification in the presence of two subscribing witnesses.
